UNITED STATES PATENT OFFICE.

FREDERICK A. BALLOU, OF MAYATN, AND ROGERS T. STAFFORD, OF EAST PROVIDENCE, RHODE ISLAND, ASSIGNEES TO E. A. BALLOU & CO., INC., OF PROVIDENCE, RHODE ISLAND, A CORPORATION OF RHODE ISLAND.

ORNAMENTATION FOR SHOES.

Application filed May 21, 1927. Serial No. 195,270.

This invention relates to ornamentation for a shoe or slipper; and has for its object to provide an ornamental ankle strap of a length to extend over the instep of the wearer substantially to the opposite side margins of the shoe upper with means for attaching or securing the strap ends to the margins of the shoe upper.

A further object of the invention is to provide an ornamental ankle strap which will extend over the instep of the wearer and over the outer surface of the opposite side edges of the shoe upper which will enhance the appearance of the foot and the shoe thereon, the opposite ends of the strap being detachably connected to the margins of the shoe to hold the strap in position.

This invention further consists in providing a strap formed of a plurality of ornamental units hingedly connected together and of a length to extend over the instep of the wearer and be detachably connected by invisible means to the margins of the shoe upper, the surface of each of the units being embellished or provided with gems to enhance the appearance of the strap when in position on the foot of the wearer.

With these and other objects in view, the invention consists of certain novel features of construction, as will be more fully described, and particularly pointed out in the appended claims.

In the accompanying drawings:

Figure 1 is a perspective view illustrating the ornamentation for a shoe in position thereon.

Figure 2 is a plan view of a portion of the strap.

Figure 3 is a side elevation of a portion of the strap showing certain of the hingedly connected link units in extended position and broken away to show their interior construction.

Figure 4 is a section on line 4-4 of Figure 1.

Figure 5 is a section similar to Figure 4 showing a modified construction of center ornament mounted on the strap.

Figure 6 is a plan view of a portion of a modified form of strap showing the same made of mesh chain.

It is found desirable by women wearing a shoe of the slipper or pump type to ornament the same to enhance the appearance of

the foot and to make more attractive the otherwise stern, tailored appearance of the standard "opera" pump; and in order to accomplish this result in a practical way, we have provided an instep strap of a length to substantially meet the opposite side margins of the shoe upper and provided means by which this ornamental instep strap may be secured to the shoe in any desired position along its margin. This strap may be made of metal and highly embellished or set with gems to give an attractive appearance to the shoe and the foot of the person wearing the same and we have also found it of advantage to provide attaching means which may be secured at any position along the margin of the shoe upper, which attaching means is ornamental and provided with a hidden jaw for gripping the margin of the shoe when the same is attached to the foot; also we have found it of advantage to make certain of the sections of the strap resilient by providing links which may telescope one within the other with yielding means for causing these to move to contracted position, the same permitting a yielding tension of the strap while the person is walking and also assisting in holding the shoe on the foot of the wearer; and the following is a detailed description of the present embodiment of our invention and showing one construction of strap by which these advantageous results may be accomplished:

With reference to the drawings, 10 designates a shoe of the pump or slipper type which has no button straps for holding the same on the foot and in order to assist in holding the shoe in position and at the same time ornament the same to a high degree, we have provided a strap 11 consisting of a series of units for securing the same to the edges 12 of the shoe upper. The units of this strap may consist of an attractive center ornament 13 of any desired shape and size which is set with gems 14 and to each edge of this ornament there is hingedly connected a series of units 15 each comprising relatively slidably links 16 and 17 moved to contracted position with a telescopic action by a spring 18 and to the ends of each of these series of extendible units there is attached an ornamental end or clip unit 19 which is provided with suitable means to engage the inner surface of the shoe and to co-

operate with the main portion of said unit 19 to anchor the end of the strap to the shoe. For purposes of illustration, each unit 19 is shown as provided with a movable attaching member 20, provided with a spur 21, capable of penetrating the leather, said attaching member being pressed by a diaphragm spring 22 against the inner surface of the shoe to hold the end of the strap in position between it and said unit 19. The surface of the end unit 19 is engraved or otherwise decorated as at 23 and has a gem set therein. Likewise the surfaces of the units 15 are engraved or ornamented by piercings 25 which co-operate with the design of an adjacent unit to enhance the appearance of the strap. We have also ornamented the surface of the sliding links 17 which are concealed when in contracted position but which when in extended position, as illustrated in Figure 3, may co-operate and assist in enhancing the appearance of the strap to beautify the same and ornament the shoe and the foot of the wearer when in position thereon. In practice, the surface ornamentation of the various elements of which the strap is constructed, including the clip units 19 conform to some general theme of ornamentation or ornamental design. Or the contours of said respective elements may be made to conform to a common ornamental theme or effect based upon their shape. Or the common ornamental theme or effect may consist of a combination of contours and surface ornamentation all cooperating to produce any desirable scheme of ornamentation or ornamental effects. Whatever the character of the selected ornamental theme may be, the end or clip units 19 conform generally thereto, and in practice conceal the attaching members 20 from view while the strap is in position on the shoe, so as to avoid any clash with the ornamental effects otherwise obtained by preventing exposure of elements which do not conform to the ornamental theme.

We may vary the construction of the strap at will and have illustrated in Figure 5 an ornament 26 as being mounted on one of the link units of the strap rather than positioning the ornament between the strap units forming a part thereof.

One of the essential features of this construction is that it may be attached to any of the standard made pumps as the attaching means at the ends of the strap are complete within themselves and may be adjusted along the edge of the shoe and secured at any desired point therealong to fit different wearers by operation of the jaw 20; also this ornamentation which we have provided has

no abrading surface on the inner side of the end unit to mar or disfigure the outer surface of the shoe over which it extends, the grip being by means of the spur 21 on the tongue 20 which engages the inner surface of the shoe to hold the strap in position.

It will be apparent that we have provided an ornamentation for a shoe which will greatly enhance the appearance of the shoe itself and also the foot of the person wearing the same and will take the place of buckles and the like which have heretofore been worn at the edge of the forward portion or toe of the shoe and attached thereto in various ways.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. Ornamentation for a shoe comprising a strap provided with an ornamental theme, said strap being of a length to extend over the instep of the wearer from one margin of the shoe upper to the other, each extremity of the strap having a clip conforming to said ornamental theme and provided on one side with attaching means cooperating with the main portion of the clip unit to removably engage the shoe.

2. Ornamentation for a shoe comprising an extensible strap formed of extendible units, each conforming to a common ornamental theme applied to the strap as a whole, clip end units connected to the respective extremities of said strap and also conforming to the said common ornamental theme, and attaching means carried by said clip units and cooperating with the main portions of said units to removably engage the margins of the shoe upper.

3. Ornamentation for a shoe comprising a strap provided with an ornamental theme, said strap being of a length to extend over the instep of the wearer from one margin of the shoe upper to the other, the extremities of said strap having clip units conforming to the ornamental theme of the strap, each of said clip units having attaching means cooperating with the main portion of the unit to removably engage the shoe, said attaching means being concealed from view by the main portions of the respective clip units while the strap is in position on a shoe.

In testimony whereof we affix our signatures.

FREDERICK A. BALLOU.
